UNITED STATES PATENT OFFICE.

CLARENCE W. WITT, OF JOHNSTOWN, PENNSYLVANIA.

DISPLAY-STAND FOR ELECTRIC-LIGHT LAMPS.

1,219,892.

Specification of Letters Patent. Patented Mar. 20, 1917.

Application filed June 15, 1916. Serial No. 103,797

To all whom it may concern:

Be it known that I, CLARENCE W. WITT, a citizen of the United States, residing at Johnstown, in the county of Cambria and State of Pennsylvania, have invented certain new and useful Improvements in Display-Stands for Electric-Light Lamps, of which the following is a specification, reference being had to the accompanying drawings.

10. This invention relates to improved display stands for electric light lamps and has for its primary object to provide a very simply constructed and serviceable device for displaying to prospective purchasers a 15 multiplicity of lamps.

The invention has for one of its more particular objects to provide a rotary display table in which the several lamps are suitably mounted, a circuit for the lamps, a central 20 relatively stationary socket to receive a test lamp, and improved means for successively closing the circuit for the display lamps as said table is rotated.

It is a further general object of my invention to provide a display device of the above character, the several parts of which are exceedingly simple in construction and can be cheaply manufactured and assembled, said device being highly serviceable and advan-

30 tageous for the attractive display of a large number of lamps of different styles.

With the above and other objects in view, my invention consists in the novel features of construction, combination, and arrangement of parts to be hereinafter more fully described, claimed and illustrated in the accompanying drawing, in which,

Figure 1 is a vertical sectional view illustrating the preferred embodiment of my im- 40 proved display device;

Fig. 2 is a plan view of the base; and

Fig. 3 is an inverted plan view of the rotary lamp carrying table.

Referring in detail to the drawing, 5 in- 45 dicates the base of the device which may be of wood or other suitable material of any desired ornamental form. In a bracket 6, centrally fixed upon the upper surface of the base 5, a tubular rod or standard 7 is suit- 50 ably mounted. 9 and 10 designate metallic circuit closing strips which are fixed at their outer ends upon the base 5 and are upwardly curved, as clearly shown in Fig. 1, the inner free ends of said strips being angularly offset upwardly, as at 11, and preferably hav- 55 ing their terminals downwardly bent or

curved. The inner free end of the circuit closing strip 10 is disposed at one side of the standard 7 and preferably closer thereto than the upwardly extending end of the 60 other circuit closing strip 9. The particular purpose and manner of operation of these metallic strips 10 and 9 will be hereinafter set forth.

12 designates the rotary table, preferably, 65 through not necessarily, of circular form in plan, which is mounted to turn freely upon the base 5, the top wall of said table being centrally provided with an opening through which the upper end of the standard 7 ex- 70 tends. A circular series of equi-distantly spaced lamp receiving sockets 13 are suitably secured in the top wall of the table 12, the lamps indicated at L being threaded in said sockets in the usual manner. Upon the 75 upper end of the standard 7 a lamp receiving socket 14 is detachably mounted and is adapted to receive a test lamp L'. This test lamp is provided for the purpose of immediately indicating an open switch or other 80 interruption with the electric circuit. Preferably, the lamp plug and socket are unthreaded so that the plug may be easily and quickly fitted into the socket or removed therefrom.

85 A plurality of depending rods 15 are fixed to the top wall of the table 12 and to the lower ends of these rods a rigid sheet of insulating material 16 is connected. This insulating sheet is provided with a central 90 opening, indicated at 17 to receive the central standard 7 and upon the under side of said insulating sheet, a metal annulus 18 is fixed in concentric relation to the opening 17. In spaced relation to this annulus, a plu- 95 rality of spaced metal plates 19 are secured, said plates being equal in number to the number of lamp receiving sockets 13 in the rotary table.

20 and 20' indicate the wires extending 100 from an external source of current through an opening 21 in the base 5. The wire 20 is connected to the fixed end of the circuit closing strip 9 and the wire 20' is connected to the fixed end of the metal strip 10. Wires 105 22 and 22' are also connected to the fixed ends of the respective circuit closing strips and extend upwardly through the tubular standard 7 and are connected to the contacts of the lamp socket 14. A wire indicated at 110 23 is metallically connected to the annulus 18 and to a metallic conductor of one of the

lamp sockets 13 connected to one side of the circuit. These conductors of the several lamp sockets are metallically connected by a wire 24, and the opposite side of the circuit through each of the plugs 13, is connected by means of a wire 25, to one of the metal plates 19.

When the several parts of the device are assembled, the free end of the circuit closing strip 9 has resilient bearing contact with the metal annulus 18, while the strip 10 is engaged upon one of the metal plates 19. The ends of the circuit wires 20 and 20' are connected to a suitable switch, and when the test lamp L' is engaged in the socket 14, the circuit will be closed through the wires 20 and 20' and the wires 22 and 22' and said lamp illuminated. The strip 9 bearing upon the annulus 18, also closes one side of the circuit through said strip, the wire 22, plate 18, wire 23 and the circular wire 24 to the corresponding conductors of the lamp circuits 13. When the table 12 is rotated, the free end of the resilient strip 10 successively passes from one of the plates 19 to another. The strip 10, as it bears upon one of said plates, closes the circuit through the wire 25 to one of the sockets so that the lamp engaged in this particular socket will be illuminated. When the end of the strip 10 moves off of this plate 19, the circuit is immediately broken to said lamp and the circuit of the next adjacent lamp is closed, when the free end of the strip 10 contacts with the next plate 19. Thus in the rotation of the table 12, it will be seen that the several lamps carried thereby, are successively illuminated, thereby accentuating the particular attractive features of the individual lamps in a distinctive manner. It is understood, of course, that the central test lamp 11' remains illuminated at all times during the rotation of the table.

From the foregoing description taken in connection with the accompanying drawings, it is thought that the construction, manner of operation and several advantages of my invention will be clearly and fully understood. The formation and arrangement of the several parts of the device being quite simple, enables the device to be constructed at relatively small manufacturing cost. It is manifest that the table 12 may be of any desired size, and that the number of lamp sockets carried thereby can be increased or decreased in number as desired. It is also within the purview of my invention to adopt various other means for mounting the rotary table than that disclosed in the accompanying drawing, which is for illustrative purposes only. In practical use I have found my improved lamp display device to be highly desirable and serviceable in interesting prospective purchasers and promoting the sale of the lamps.

While I have herein described the preferred form, construction and arrangement of the several parts, it is to be understood that the same are susceptible of considerable modification; therein and I therefore reserve the privilege of adopting all such legitimate changes as may be fairly embodied within the spirit and scope of the invention, as claimed.

Having thus described this invention, what I desire to claim as new and secure by Letters Patent, is:—

1. An electric lamp display device including a base, a table rotatably mounted thereon, a plurality of spaced sockets carried by the table, to receive the lamps to be displayed, a central relatively stationary socket mounted above the table to receive a test lamp, and a circuit for said lamps including circuit closing strips fixed upon the base, and means carried by the table to be engaged by the respective circuit closing strips to close the circuit and successively illuminate the display lamps in the rotation of the table, said means including a conductor in constant engagement with one of said strips to maintain the circuit closed through the test lamp.

2. An electric lamp display device including a base, a table rotatably mounted thereon, a plurality of spaced sockets carried by the table to receive the lamps to be displayed, a centrally fixed standard projecting above the table, a socket upon the upper end of said standard to receive a test lamp, and a circuit for said lamps including spaced resilient circuit closing strips connected to opposite sides of the circuit, a metal annulus carried by the table and engaged by one of said strips, and means at all times connecting said annulus to one side of the circuit through the lamp sockets on the table, and spaced metal plates carried by the table and individually connected to the respective lamp sockets and adapted to be successively engaged by the other of the circuit closing strips in the rotation of the table, whereby the circuit is successively closed through the display lamps when the table is rotated.

3. An electric lamp display device including a base, a vertically disposed standard centrally mounted upon said base, a table rotatable upon the base and having a central opening to receive said standard, a plurality of spaced sockets carried by the table to receive the lamps to be displayed, a socket fixed upon the upper end of said standard, a test lamp adapted to be engaged in the latter socket, spaced circuit closers mounted upon the base, a circuit for said lamps including a metallic connection between one side of the circuit through said display lamp receiving sockets, a series of spaced contacts respectively connected to the opposite circuit terminal of said sockets, said contacts being

adapted to be successively engaged by one of the circuit closers upon the rotation of the table, wire connections between the circuit closers and the socket terminals for the 5 test lamp, and an additional contact plate carried by the table and metallically connected to the connection between the terminal sockets, whereby the test lamp is at all

times illuminated in the rotation of the table.

In testimony whereof I hereunto affix my signature in the presence of two witnesses.

CLARENCE W. WITT.
